US0D1087024S

(12) **United States Design Patent** (10) Patent No.: **US D1,087,024 S**
(45) Date of Patent: ** Aug. 5, 2025

(54) **CURRENT TRANSFORMER**

(71) Applicant: **Xiamen Milesight Iot Co., Ltd.**,
Xiamen (CN)

(72) Inventors: **Jinrui Liu**, Fujian (CN); **Shanyan Que**,
Fujian (CN)

(**) Term: **15 Years**

(21) Appl. No.: **35/522,577**

(22) Filed: **Jun. 13, 2024**

(80) **Hague Agreement Data**

Int. Filing Date: **Jun. 13, 2024**

Int. Reg. No.: **DM/240652**

Int. Reg. Date: **Jun. 13, 2024**

Int. Reg. Pub. Date: **Oct. 11, 2024**

(30) **Foreign Application Priority Data**

Apr. 12, 2024 (CN) 202430203947.7

(51) **LOC (15) Cl.** **13-02**

(52) **U.S. Cl.**

USPC **D13/110**

(58) **Field of Classification Search**

USPC D13/110, 101, 107, 112, 118, 123, 162,
D13/184, 199; D14/357

CPC H02M 7/068; H01F 27/00; H01F 27/02;
H01F 27/002; H01F 27/06; H02B 1/50

See application file for complete search history.

(57) **CLAIM**

The ornamental design for a current transformer as shown and described.

DESCRIPTION

1. Current transformer
2. Current transformer
- 1.1 : Perspective
- 1.2 : Perspective
- 1.3 : Front
- 1.4 : Back
- 1.5 : Left
- 1.6 : Right
- 1.7 : Top
- 1.8 : Bottom
- 2.1 : Perspective
- 2.2 : Perspective
- 2.3 : Front
- 2.4 : Back
- 2.5 : Left
- 2.6 : Right
- 2.7 : Top
- 2.8 : Bottom

The broken lines shown represent the portions of the current transformer that form no part of the claimed design.
